INVENTOR:

W. C. Wells

United States Patent Office.

WILLIAM C. WELLS, OF PHILADELPHIA, PENNSYLVANIA.

Letters Patent No. 78,560, dated June 2, 1868.

IMPROVEMENT IN ICE-CREEPERS.

The Schedule referred to in these Letters Patent and making part of the same.

TO ALL WHOM IT MAY CONCERN:

Be it known that I, WILLIAM C. WELLS, of Philadelphia, in the county of Philadelphia, in the State of Pennsylvania, have invented a new and improved "Creeper;" and I do hereby declare that the following is a full and exact description thereof, reference being had to the accompanying drawings, and to the letters of reference marked thereon.

The nature of my invention consists in the construction of a "creeper," composed of "leather," or other soft and pliable material, upon which "spurs" are fastened by means of "washers," and by "riveting," the said "creeper" to be worn beneath the sole of the "shoe," and to be attachable thereto, and detachable therefrom, by means of straps or other suitable fastening, the use of the said "creeper" being to prevent the wearer from slipping whilst walking upon sidewalks that are covered with ice.

Figure 1 is a bottom view of the creeper, showing the "spurs" *a a a a*, and the washers *B B B B*.

Figure 2 is a top view, or the "reverse" of fig. 1, and shows the washers *B' B' B' B'*, and the riveted ends of the "pivots" *c c c c*.

Figure 3 shows the "spur" *a*, with its pivot *c*, and the washers *B B'*.

Figure 4 shows a "shoe," and the manner in which the "creeper" should be attached.

I construct my "creeper" as follows, to wit: Through the aperture in the "washer" *B*, fig. 3, I pass the pivot *c* of the "spur" *a*, until the shoulder of the spur bears upon the washer; the pivot *c* is then passed through the piece of "leather," *E*, which is perforated for the purpose, until the end of the said "pivot" projects beyond the surface of the leather, opposite to where it entered. A second "washer," *B'*, is then placed on the projecting end of the "pivot" *c*, fig. 2, which brings the leather between the two washers. The projecting end of the pivot *c* is then riveted down upon the "washer" *B'*, thus fastening the spur *a* and both "washers," *B B'*, firmly upon the leather. This process is repeated until the requisite number of "spurs" and "washers" are fastened upon the leather. Straps and buckles are then attached to the leather, and the "creeper" is complete.

I do not claim as my invention the attaching of "spurs" to the bottom of a shoe, to prevent the wearer from slipping, nor do I claim the construction of a "creeper" to be fastened to the shoe as now; but

What I do claim as my invention, and for which I desire to secure Letters Patent, is, viz:

Claim.

A "creeper," composed of a piece of leather or other soft material; with metal "spurs" fastened thereon, by means of metal "washers," and by riveting, when said piece of leather, with spurs thereon, is constructed separate from the shoe, and is intended to be worn beneath the sole of the shoe, and is attachable to and detachable from the shoe, substantially as shown and described.

WILLIAM C. WELLS.
